UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

TAPE-REEL FOR SEWING-MACHINES.

1,286,956.

Specification of Letters Patent. Patented Dec. 10, 1918.

Application filed March 6, 1917. Serial No. 152,548.

To all whom it may concern:

Be it known that I, ALBERT H. DE VOE, a citizen of the United States, residing at Westfield, in the county of Union and State 5 of New Jersey, have invented certain new and useful Improvements in Tape-Reels for Sewing-Machines, of which the following is a specification, reference being had therein to the accompanying drawings.

10 This invention relates to attachments for sewing machines and particularly to means for holding a roll of tape and cops of thread in a convenient position relative to such machines.

15 It has for its object the construction of a tape-reel that is simple and cheap to manufacture, that is easy to replenish and replace, and that is adapted to accommodate various widths of tape.

20 It also has for its object the utilization of the tape-reel support for sustaining a plurality of cop-holders in a position clear of the support of the sewing machine head and for a further object it has the provision 25 of means for conveniently multiplying the number of cop-holders.

Briefly described the construction comprises a supporting bracket having a pair of bearing lugs supporting a horizontal ro-

30 tatable rod at one end of which is fixed a spider-wheel carrying a spring-actuated finger-lever for gripping a pin extending from a second spider-wheel. Between the spider-wheels a roll of tape is adapted to 35 be received.

A vertical rod is also supported by the bracket and a plurality of relatively fixed cop-holders are secured to the vertical rod in such relation that one or more individual 40 cop-holders may be removably mounted be-

tween adjacent fixed cop-holders.

The invention further consists in certain details of construction which will appear in the following description of the embodiment 45 of the invention shown in the accompanying drawings in which Figure 1 is a perspective view of the attachment and Fig. 2 is a sectional detail showing a locking lever.

A bracket 1 having a base flange 2 is secured in any suitable manner as by screws 3 to the flange 4, or other convenient part of a support for the head of a sewing machine (not shown). The bracket 1 is curved and its substantially horizontal free end carries 55 spaced bearing lugs 5 and 5' which are

apertured horizontally to receive a reel-supporting rod 6. Collars 7 and 8 are adjustably secured to the rod 6 on opposite sides of lug 5, the collar 7 being arranged between the lugs to receive the thrust of a spring 60 9 coiled about the rod. Rotation of the rod 6 in the lugs is thus resisted by the friction between one of the collars and the contiguous part of one of the lugs.

To the free end of the rod 6 a spider-wheel 10 is secured in a suitable manner and a lug 11 fixedly carried by one of the spokes 12 of the wheel is bifurcated to allow movement of a lever 13 pivoted intermediate its ends at 14 to the ears 15 of the lug 11. A 70 spring 16 pocketed in the lug 11 as indicated in Fig. 2 bears on one arm of the lever 13 and tends to turn it about its pivot so as to cause its toe 17 to jam a second rod or pin 18 against the walls defining the aperture 75 19 in one end of rod 6. The rod 6 is of course cut away as indicated at 20 to allow movement of the toes 17 of the lever for this purpose. The rod or pin 18 is rigidly connected to a second spider-wheel 21 and it is 80 of sufficient length to allow the spider-wheels to be spaced in parallelism varying distances apart in order to accommodate rolls of tape of different widths.

It will be understood that when the reel 85 is exhausted and is to be replenished the lever 13 may be pressed to release the pin 18 and permit removal of the outer spider-wheel 21 which is equipped with a wing or finger-piece 22 for facilitating handling 90 thereof. With the outer spider-wheel in one hand the operator may very conveniently place a new roll on the pin 18. Then after inserting the pin 18 in the aperture 19 the outer spider-wheel 21 may be quickly 95 moved sidewise toward the relatively fixed inner spider-wheel 10 until stopped by the intervening roll of tape against the edges of which the spider-wheels will be snugly held by the automatic action of the spring- 100 pressed lever 13. It will be noticed from an inspection of Fig. 2 that the toe portion 17 of the lever which is shown in gripping relation with the pin 18 is slightly to the right (Fig. 2) of a point vertically beneath the pivot 14. Thus endwise sliding movement of the pin 18 is permitted to the right (Fig. 2) to bring the spider-wheels or side frames together but if it is attempted to 105 separate the outer and inner spider-wheels 110

movement of pin 18 to the left will be prevented by the locking action of the toe 17 of the lever 13.

By adjusting the collars 7 and 8 the rod 6 may be shifted to bring the reel into desirable relationship with the stitching point of a sewing machine. Also by providing a slight frictional resistance to the rotation of the supporting rod 6 slack in the tape between the reel and the stitching point may be eliminated.

It has also been found desirable to locate cop-holders on the bracket 1 utilizing it for the two-fold purpose of supporting the reel and the cops for the several needles which are almost invariably used when tape is being stitched.

For this purpose a rod 30 is adjustably secured by a screw 31 in the vertical bore in the lug 32 on the bracket 1 and a suitable number, preferably four, of cop-holders 33 are fixed to the rod 30 by the integral arms 38.

In multiple-needle machines the number of the needles is frequently varied to meet the demands of the work and it is desirable to provide for multiplying the number of cop-holders.

For this purpose the fixed cop-holders 33 are so arranged and spaced that one or more individual cop-holders 34 may be removably located between adjacent fixed cop-holders 33 as indicated on the drawing. The arm 35 of any individual cop-holder 34 is T-shaped in cross-section and its horizontal flange 36 is adapted to rest on the edges of a pair of fixed cop-holders 33 while its toe 39 on the vertical flange engages under the junction of the integral arms 38 supporting the fixed cop-holders 33.

While I have employed the term spider-

wheel in the description of the reel because of its aptness it is obvious that any suitable form of side frame may be used in lieu of the specific construction shown.

Having thus set forth the nature of the invention, what I claim herein is:—

1. In a tape-reel, a relatively fixed spider-wheel, means for supporting the same, a second spider-wheel movable relatively to said fixed spider-wheel and having a supporting pin adapted to be carried by said supporting means, and a spring-actuated friction clutch for securing said pin to said supporting means to hold the spider-wheels in any one of various spaced relations.

2. In a tape-reel, inside and outside spider-wheels, a supporting rod arranged centrally of and extending at substantially right angles to said inside spider-wheel, said rod being provided with a longitudinally extending aperture in one end, a pin arranged substantially centrally of and extending at right angles to the outside spider-wheel, said pin being adapted to enter said aperture, and a spring-actuated lever movably carried by said inside spider-wheel, said lever having a toe portion adapted to grip said pin in said aperture.

3. In a tape-reel, a pair of relatively adjustable spider-wheels, two coaxially arranged rods supporting one each of said spider-wheels, means for holding said rods against relative movement in one direction but permitting movement in an opposite direction, a bracket having duplex apertured ears for supporting said rods rotatably, and means frictionally engaging one of said ears for resisting rotation of said rods.

In testimony whereof, I have signed my name to this specification.

ALBERT H. DE VOE.
